& DAVIS COMPANY, A CORPORATION OF MASSACHUSETTS.

MESH MACHINE.

Application filed November 2, 1923. Serial No. 672,271.

This invention relates to machines for making link mesh fabric such as is commonly used in the manufacture of ladies' hand bags and other similar articles. More specifically, 5 the invention is directed to the provision of a machine for the production of link mesh of an ornamental character and containing links of different colored materials, arranged in the fabric according to predetermined designs or patterns.

Machines of various types are in use at the present time for making link mesh and these machines produce mesh in the form of a sleeve or in a flat web or strip. The links of 15 which the fabric is composed are usually made of wire of a precious or semi-precious metal and in some of these machines the wire is led from a supply to link forming tools by which lengths of wire are severed and formed 20 into rings intermeshing with those of the piece of mesh. These machines operate step by step with the link forming tools inserting a link at each period of rest. Sometimes several sets of tools are provided and this increases 25 the rate of production, but each operation of each set of the tools forms a single link. In other machines, the forming tools are fed with staples previously made from the wire and contained in magazines, one for 30 each set of tools, and a multiplicity of tools is arranged in a bank so that a flat strip of mesh may be made one complete row of links at a time. In either type of machine, a single kind of wire is used and the fabric produced 35 consequently has a plain, undecorated appearance.

The machine of the present invention, however, is designed to produce ornamental mesh and is so arranged and constructed 40 that links of different kinds of material may be incorporated in the fabric as the mesh making operation progresses. The different kinds of material have different colors and the operation of the machine is automatically 45 controlled so that various patterns may be formed in the fabric by links of contrasting colors.

The principles of the invention may be utilized in connection with mesh making machines of any of the various types, such as machines for making mesh in the form of a sleeve or in the form of a flat strip, machines in which the piece of mesh moves either

downwardly or upwardly as it is made, and machines in which the mesh is produced 55 either link by link or row by row.

The type of machine which is considered best is that in which the mesh is made in the form of a sleeve which is moved upwardly as the operation of adding rings to the piece 60 progresses. This machine is provided with a plurality of supplies of different wires, or wires presenting a different surface appearance, and automatic mechanism for regulating the operation of the machine to make 65 links from these different wires in any predetermined order of succession, to begin making links from any one of the wires at any predetermined point and to shift from one wire to another after any predetermined 70 number of links has been made. This automatic mechanism is under the control of a master device of such a construction that it can be set to produce any desired pattern and a selected pattern can be produced repeatedly 75 as often as desired.

In mesh making machines of the sleeve type, the wire is fed from the supply to link forming tools which make the rings and insert them so as to intermesh with rings at 80 the edge of the fabric. The operation of the tools serves to cut off a piece of wire, bend it to the form of a staple, advance the staple so as to mesh it with rings of the piece of mesh, and then close the staple to form the 85 link. In arranging such a mechanism for use in the manufacture of multi-color mesh, a movable block may be employed for guiding the wire to the tools, this block having a plurality of passage ways for strands of wire 90 from a plurality of supplies. The wire from these supplies may be fed into the passages by any suitable feeding mechanism, and preferably small metallic tubes are employed, extending from the feeding mechanism to the 95 passages in the block so as to guide the wire properly. This movable block with the several passages through it for the wires from the several sources of supply may be moved as may be required to bring any selected one 100 of the several passages opposite the proper point with relation to the link forming tools for feeding the desired wire to these tools.

The automatic master mechanism which controls the change from one piece of wire 105 to another is driven by the power-driven

devices of the machine and is actuated in correspondence with the step by step movement of the piece of mesh relative to the tools and the operation of these tools in the periods of rest of the step by step movement. This master controller governs the operation of the feeding mechanism for the several supplies of wire, and also the position of the movable block above referred to; 10 that is, at selected intervals the control mechanism functions to discontinue the operation of the feeding mechanism for one supply of wire, bring into action the feeding mechanism for another supply of wire, 15 and at the same time move the block to carry the passage for the wire to be fed thereafter opposite the feeding point of the link forming tools.

This master control mechanism includes a 20 pattern device which determines the order of succession of the feed of the several supplies of wire, the times in the operation of the machine when the shift will be made from one supply to another, and the number of links which will be made from each supply before shifting to another supply. This pattern device may conveniently take the form of a rotary support and a multiplicity of radial devices mounted on the support in different positions of adjustment whereby a single mechanism may be employed for making mesh having a multiplicity of different designs. These devices are of different dimensions and the number 30 of different kinds corresponds to the number of different kinds of wire which are to be used. Each device is effective to cause wire to be fed from a selected supply, and also to cause the movable block to assume 35 a position in which this wire will be properly directed to the link forming tools. The devices are brought successively into operation at predetermined intervals, and consequently the order of the devices in this sequence will determine the order of succession in which the different wires are used for links, and also the times when the shift will be made from one supply to another. The 40 actuation of the means whereby the devices 45 carried by the support are brought into action is so correlated with the operation of the link forming tools that the arrangement of the devices on the support and the intervals at which successive devices are rendered effective to perform their functions 50 will determine the number of links to be made from a given supply before a shift is made. Since all of the several factors involved in production of the pattern in the 55 mesh are variable, the master control mechanism may be adjusted to produce patterns in practically unlimited variety, and the kind of wire of which any single link in the mesh is to be made may be determined in advance. 60 65 When the design is such that the shift

from one supply of wires to another is to occur only when a row or a number of rows of links has been completed, the construction of the pattern device may be considerably simplified. In striped mesh, for instance, the stripes consist of a number of rows of links of the same kind of material and for the production of such mesh it is sufficient that the pattern device perform its functions only when the end of a row 70 has been reached. While such mesh may be made on the pattern device previously described, it is also possible to dispense with the radial device and to make use of a rotary support which has been given a suitable 75 configuration so that it will perform the same functions as the support with the devices mounted on it. Such a support will produce but a single pattern but a number of supports designed to produce different 80 patterns may be made up and used in the machine as desired.

With a pattern device of the form above described, the pattern is produced by means of a series of adjustable devices, brought 90 successively into operative position. When each unit of the series has been brought into action, the pattern is complete and the same figure or group of figures in the pattern will be repeated as the series of devices comes 95 into action again. The length of the pattern so repeated will depend on the number of units in the series, all other factors remaining constant, and when a very long pattern is to be made, it may be convenient to make 100 use of a support for the adjustable devices in the form of a chain. This may be of indefinite length so that the length of the pattern is unlimited and may be endless if repetition is desired. The action of the devices, however, is the same as that previously described.

In the accompanying drawings I have illustrated that embodiment of the invention which is now preferred, and in these drawings,

Fig. 1 is a vertical longitudinal sectional view of the complete machine,

Fig. 2 is a top plan view,

Fig. 3 is a horizontal sectional view with certain parts broken away,

Figs. 4, 5, 6 and 7 are detail sectional views of the link forming devices showing the parts in the different positions which they assume during the link forming operation,

Figs. 8 and 9 are detail sectional views showing the action of the outer link forming device,

Fig. 10 is a longitudinal sectional view of one of the outer link forming tool assemblies,

Fig. 11 is an end elevation of the machine showing the pattern control devices,

Fig. 12 is a detail elevation of a clutch assembly,

Fig. 13 is a view of the color plate,

Fig. 14 is a view of a modified form of color plate,

Fig. 15 is a sectional view of the plate shown in Fig. 14,

Figs. 16, 17, 18 and 19 are views in elevation and section of the color blocks which fit in the plate shown in Fig. 14,

Figs. 20 and 21 are cross-sectional and plan views respectively of a modified form of selector disc attachment,

Figs. 22 and 23 are plan and sectional views respectively of selector blocks designed to be used in connection with this form of selector disc attachment,

Fig. 24 is a sectional view of the wire feed devices taken on the line 24—24 of Fig. 3,

Fig. 25 is an elevational view of a detail of the wire feed mechanism,

Fig. 26 is a sectional view taken on the line 26—26 of Fig. 25,

Fig. 27 is a rear end view of the wire block,

Fig. 28 is a side elevation of the wire block,

Fig. 29 is a front end view,

Fig. 30 is a top view of the wire block,

Fig. 31 is a side view of a modified form of color control device,

Fig. 32 is a view partially in section showing the color chain to be used therewith,

Figs. 33 and 34 are top and bottom plan views, respectively of the color lugs used on this chain,

Figs. 35 and 36 are views of a detail of the modified form of color wheel showing the chain in place on the wheel,

Fig. 37 is a view of a piece of mesh with a pattern formed therein of bands of contrasting colors, and

Fig. 38 is a view of another piece of mesh showing another type of pattern formed therein of links of contrasting colors.

Referring now to the drawings, the machine is seen to consist of a table 39 mounted on legs 40 in any convenient location. Supported centrally of the table is a block 41 cylindrical in form and anchored in place by an extension 42 which passes through an aperture in the table and which is held in place by a nut 43 threaded on its lower end. A ring 44 is mounted in a channel along its upper edge, and the surface of this ring is provided with a spiral groove. Secured in place on the top of the block is a second block 45, held in position by means of bolts 46. A ring 47 is mounted to run freely in a channel in this smaller block 45, and the outer surface of the ring 47 is provided with a series of alternate vertical ridges and depressions. This block 45 rests on ball bearings 48 which run on the top of the ring 44. Encircling the block 45 and the upper end of the block 41 is a sleeve 49, the inner surface of

which is provided with a series of alternate ridges and depressions also arranged vertically. The sleeve 49 has a flange 50 formed at its upper end, and this flange overlies a ring-like support 51 mounted on the table, and rests on ball bearings 52 carried by the support. Also, the edge of the flange is provided with a plurality of ratchet teeth 53 by means of which the sleeve may be given a step-wise rotation by devices later to be described.

The links in the fabric tilt in opposite directions in successive rows as will be seen in Fig. 4, and this tilting is taken advantage of in providing the support for the piece of mesh. For this purpose the sleeve 49 and the ring members 44 and 47

are provided with the spiral grooves and the ridges and depressions referred to, and the sleeve 49 is positioned closely enough to the ring members so that rings in the mesh will engage in the depressions in the sleeve 49

and also in the spiral grooves in the ring 44. Consequently as the sleeve 49 is given a rotational movement the finished mesh is carried with it and since the collar 44 is stationary the mesh is caused to move up the spiral during this rotation.

The sleeve of mesh therefore moves in an upward spiral path, step by step, and at each position of rest it is disposed in proper relation to the forming tools so that new links may be added.

As the finished sleeve of mesh passes upwardly beyond the tube of the sleeve 49 it may be supported in any convenient manner.

In the machine illustrated there are two link forming assemblies located on opposite sides of the block 41. These assemblies act simultaneously and add links lying in successive vertical rows. Accordingly, when two such assemblies are in operation, a complete rotation of the sleeve 49 represents the formation of two complete rows of links around the mesh sleeve and the ring 44 must have a double spiral groove. These assemblies are similar in construction and but one of them need be described.

Mounted in brackets 54 below the table 39 is the main drive shaft 55. At one end, this shaft is provided with a pulley 56 and also with a clutch device, indicated generally at 57, by means of which the shaft may be driven with the pulley or released therefrom as may be desired. Also, at the other end the shaft is provided with a hand wheel 58,

by means of which the machine may be operated by hand as may be occasionally necessary to insert one or more links which the forming tools may have failed to insert properly in the fabric. Near each end the shaft is provided with a bevelled gear 59,

which meshes with a similar gear 60 fast on a shaft 61 which extends vertically through a bearing member 62 mounted in the table.

Fast on the shaft 61 is a face cam disc 63

which is provided with a series of alternate ridges and depressions also arranged vertically. The sleeve 49 has a flange 50 formed at its upper end, and this flange overlies a ring-like support 51 mounted on the table, and rests on ball bearings 52 carried by the support. Also, the edge of the flange is provided with a plurality of ratchet teeth 53 by means of which the sleeve may be given a step-wise rotation by devices later to be described.

The links in the fabric tilt in opposite directions in successive rows as will be seen in Fig. 4, and this tilting is taken advantage of in providing the support for the piece of mesh. For this purpose the sleeve 49 and the ring members 44 and 47

are provided with the spiral grooves and the ridges and depressions referred to, and the sleeve 49 is positioned closely enough to the ring members so that rings in the mesh will engage in the depressions in the sleeve 49

and also in the spiral grooves in the ring 44. Consequently as the sleeve 49 is given a rotational movement the finished mesh is carried with it and since the collar 44 is stationary the mesh is caused to move up the spiral during this rotation.

The sleeve of mesh therefore moves in an upward spiral path, step by step, and at each position of rest it is disposed in proper relation to the forming tools so that new links may be added.

As the finished sleeve of mesh passes upwardly beyond the tube of the sleeve 49 it may be supported in any convenient manner.

In the machine illustrated there are two link forming assemblies located on opposite sides of the block 41. These assemblies act simultaneously and add links lying in successive vertical rows. Accordingly, when two such assemblies are in operation, a complete rotation of the sleeve 49 represents the formation of two complete rows of links around the mesh sleeve and the ring 44 must have a double spiral groove. These assemblies are similar in construction and but one of them need be described.

Mounted in brackets 54 below the table 39 is the main drive shaft 55. At one end, this shaft is provided with a pulley 56 and also with a clutch device, indicated generally at 57, by means of which the shaft may be driven with the pulley or released therefrom as may be desired. Also, at the other end the shaft is provided with a hand wheel 58,

by means of which the machine may be operated by hand as may be occasionally necessary to insert one or more links which the forming tools may have failed to insert properly in the fabric. Near each end the shaft is provided with a bevelled gear 59,

which meshes with a similar gear 60 fast on a shaft 61 which extends vertically through a bearing member 62 mounted in the table.

Fast on the shaft 61 is a face cam disc 63

on which rests a follower 64. The shaft 61 is provided, above the bearing 62, with a disc 65 resting on ball bearings 66 which run on the flat upper surface of the bearing 62. Extending upwardly from the disc 65 and disposed eccentrically thereon is a pin 67 on which is rotatably mounted a block 68. This block enters a recess formed in a block 69, the lateral edges of which enter guide-ways 70 formed in upright members 71 secured to the table. As is shown more clearly in Figs. 2 and 11, this block enters between the sides of a yoke 72 formed by spaced flanges mounted on the rear end of the outer link forming tool assembly.

This assembly is shown in Fig. 10 and it will be seen from Fig. 11 that the assembly is disposed in a suitable slot 73 formed in the upper face of the block 69. With this arrangement, as the shaft 61 is driven from the main shaft, the eccentricity of the pin 67 acting on the block 69 will cause the forming assembly to move toward and away from the central block 41 about which the mesh is formed.

This link forming assembly, as has been explained, is mounted in place in a convenient manner in the block 69 and it consists of a cylindrical housing 74 in the forward end of which is mounted a plunger consisting of a cylindrical body 75 in which is threaded a tubular member 76, the outer end of which carries a pair of prongs 77. Threaded in the member 74 and extending through the channel therein is a die-rod 78, the outer end of which has a die 79, the face of which is provided with a channel shown more clearly at 80 in Fig. 4. The member 76 is threaded into the body 75 and held in place therein by a lock nut 81. Also threaded on the member 76 is a depending lug 82 held in place by a lock nut 83. In the channel formed in the housing 74 is a spring 84, one end of which bears against the inner end of the channel, the other end bearing against the face of the body 75. Also, the assembly is held in place in the slot 73 formed in the upper face of the block 69 by means of a flange 85 formed integrally with member 74 and a disc 86 threaded on the rear end of the member 74 and held in place thereon by a lock nut 87. The die-rod 78 is threaded into the rear end of the member 74 and is held in place therein by a lock nut 88. With this arrangement it will be seen that the position of the rod 78 with reference to the member 74 may be given various adjustments and the tubular member 76 carrying the prongs 77 may also be given various positions of adjustment by means of the mounting shown. The forward end of the member 76 enters a channel formed in the block 89 mounted on the table and a cap 90 is bolted on the top of the block so as to overlie the rear end of this channel.

Pivotedly mounted in a suitable channel in the block 89 is a lever 91, the forward end of which carries a forming mandrel 92. At its rear end this lever rests on the upper end of a rod 93, the lower end of which carries a cam follower 64 resting on the face cam 63. As the cam 63 is rotated with the shaft 61, the rod 93 moves up and down at the desired instant to bring the forming mandrel into and out of operative position in front of the forming tool. The rear end of the rod 91 is held against the upper end of the rod 93 by means of a spring 94. Pivotedly mounted on a rod 95 passing through the block 89 is a knife member 96 and secured to the rod 94 is a lever 97, the rear end of which is engaged by the pivoted lever 98 which is rocked by a vertical rod 99 carrying a cam follower 100 which bears against a cam 101 mounted on the main shaft 55. This rod 99 is encircled by a spring 102 which maintains the follower against the face of the cam.

Referring now to Figs. 4, 5, 6 and 7, it will be seen that a wire feed block 103 is mounted on a rod 104 against the inner face of the block 89 and a leaf spring 103' attached to the block 89 bears against the upper surface of the wire block. The rod 104 rests at its lower end on another rod 105 which in turn rests on the end of a lever 106 (see Fig. 24), loosely pivoted on a shaft 107 adjustably mounted between threaded pins 108 secured in brackets 109 from the lower face of the table at the rear. This rod 106 is provided with a roller 110 which rests on a cam 111 mounted on a rock shaft 112 secured in brackets 113 depending from the rear edge of the table. The cam 111 is provided with surfaces of different heights depending on the number of different kinds of wire which are to be fed. In the present instance the machine is designed to operate with three different kinds of wire and the cam will, therefore, have surfaces of three different heights. By mechanism which will later be described, the shaft 112 is rocked at the proper time so as to raise the lever 106 and, through the various rods, the wire feeding block 103, so that the proper wire channel is brought into operative position. As the wire of which a particular link is to be formed is fed through its channel into the path of the link forming tool, the end of the wire will enter a notch in a spring-held pin 114 mounted in the block 89. Upon the feeding of such a length of wire the parts are timed so that the outer link former moves forward so that the prongs 77 will engage this length of wire 115. At this time the mandrel 92 has moved up in front of the wire and as the prongs strike the wire the desired length is severed by the knife 96 moving to operative position. The severed portion is held against displacement by rea-

son of the spring pressure exerted upon it by the spring-held rod 114. The link forming assembly continues to move forward and by the cooperation of the prongs, the mandrel 92 and the inner forming rod 78, the wire is bent into the staple form with the bend of the staple lying in the channel 80. The knife 96 now moves downwardly to an operative position as does also the mandrel 92. The outer link forming assembly, however, continues its movement carrying with it the staple.

Mounted centrally of the block 41 is a rod 116 carrying in its lower end a roller 117 which rides on a cam 118 mounted on the main shaft. At its upper end the rod 116 has cam surfaces 119 and mounted in channels extending diametrically across the block 41 are inner die members 120, the rear ends of which bear against the cam surfaces 119. At the forward ends these die members have dies which are channeled as at 120', these channels being similar to the channels 80 formed in the die rods 78 and being designed to cooperate therewith so as to close the staple and complete the link. Also, the outer ends of the die members have shoulders 121 against which bear leaf springs 122 secured in suitable recesses in the block 41.

Referring to Fig. 4, it will be seen that the mesh, a few links of which are indicated at 123, is supported between the blocks 89 and 41, the sleeve of mesh being held in this position by the support formed by the sleeve 49 and the rings 44 and 47. As the outer link former as has previously been described, moves forward carrying with it the staple formed of the severed length of wire, the legs of this staple are inserted through two links at the edge of the piece of mesh, the latter having been previously moved so that the staple will be added at the proper point. When the outer link forming tool has reached a certain point in its travel, as shown in Figs. 8 and 9, the inner member 120 moves forward under the propulsion of the rod 116 to meet it and when the parts have reached the desired position the lug 82 will strike against a pin 124 formed in the rear face of the block 89. This will prevent further movement of the member 76, the prongs at the end of which have now reached the point indicated in Fig. 8 lying closely against the end of the inner tool. However, the member 74 carrying with it the rod 78, continues to advance by reason of the movement of the block 69, and this movement causes a compression of the spring 84. The rod 78 eventually reaches the position shown in Fig. 9, in which the ends of the staple carried in the channel 80 have entered the channel 121' being there closed to form the complete link by the cooperation of the forming tools. During this final closing of the link, the prongs serve to

insure that the ends of the staple will properly enter the channel 121'. The link has now been formed and the parts are to be restored to their normal positions. The inner forming tool is forced back by the leaf spring 122 as the rod 116 moves downwardly. The block 69 also moves back carrying with it the housing 74, and the member 76 is given a return movement by means of a lever 125 pivoted in a bracket 126 which is mounted on the upper face of the table. Through the lower part of this bracket extends a pin 127, which is acted upon by a cam projection 128 formed on the disc 65. As this disc 65 rotates, the cam moves to an operative position at the proper instant moving the pin 127 outwardly, thus rocking the lever 125 on its pivot. This rocking movement causes the lever to act on the lug 82 and thus restore the member 76 to its original position as indicated in Figs. 4, 5 and 10. The entire assembly then moves back to the extreme rearward position and the cycle of operations is repeated as a new link is added.

From an examination of the piece of mesh illustrated in Fig. 4, it will be seen that the links of successive rows tilt in opposite directions and this tilting ordinarily takes place naturally when the newly formed link is released from the dies. However, in some instances it may be desirable to supply means for producing this effect and this may be done by a rod which strikes the link as it is released and gives it the proper tilt or else suitably directed air blasts may be employed for the same purpose.

Reference has previously been made to the stepwise rotation of the sleeve 49 as new links are added to the mesh. This rotation is produced by means of a cam 129 mounted on the main shaft 55. Bearing on the face of this cam is a follower 130, fast on the shaft 131, suitably supported in bearings in the table. The follower 130 is held against the face of the cam by means of a spring 110 acting on a lug 131 fast on the shaft 131. The shaft 131 extends upwardly through a lug 132, forming part of the support 51, and at its upper end carries a channeled block 133. In the open end of the channel is a pawl 134, which engages the ratchet teeth 53 formed on the flange 50. The pawl has a rearward extension lying in the channel which is provided with a pin 135 which extends upwardly through a slot formed in the upper face of the block 133. In the rear end of the channel is a spring 136 which maintains the pawl normally in operative position, but as the shaft 131 is rocked by its cam the pawl is free to ride over the teeth of the ratchet by compressing the spring 136. The reverse movement of the rock shaft 132 causes the sleeve 47 to be fed forward by one ratchet tooth. A lug 137 extending from the support 51 opposite the lug 132 carries a

block 138, which is provided with a leaf spring 139 which engages in the ratchet teeth and acts as a stop pawl to prevent reverse movement of the sleeve.

It has previously been explained that the wire of which the links is made is fed into the position where it may be severed and bent into the staple form through a feed block 103, carried on the rod 104. This feed block is shown more clearly in Figs. 27 to 30, inclusive, and is provided with a plurality of channels, in this case three, through which the wire passes from the source of supply to the forming tools. At the rear end the block has an extension 140 bolted in place. This extension provides an anchorage for the ends of a plurality of flexible tubes 141 through which the wire passes from the reels to the channels. The channels 142 with which the tubes are in registry are spaced apart a considerable distance at their rear ends but converge and then run parallel at their forward ends. Also a plate 143 mounted on the face of the block, serves to hold the wire in these channels after it has left the tubes. Each of the flexible tubes 141 runs to a feeding device for feeding wire from a source of supply.

These feeding devices are shown in Figs. 25 and 26. Extending upwardly from the table along the rear edge thereof, are blocks 144, channeled vertically. Mounted on shafts 145 rotatably mounted in the block 144, are feed rolls 146 provided with a central groove 147 of sufficient depth so that the wire will be tightly gripped between the cooperating rolls and fed forward the requisite distance as the rolls are rotated. The shaft 145 of the upper roll rests in slots in the block 144 and is pressed downwardly by means of springs 149 which bear against blocks resting on the upper surface of the shafts 145. This arrangement of springs insures that the rolls will grip the wire with a resilient grip and feed it forward without injuring it. The top of the slots in which the upper shaft 145 rests is covered by a block 150 bolted to the block 144. On the lower shaft 145 beyond the block 144 is a ratchet wheel 151 and pivotally mounted on the end of this shaft is an arm 152, on which is pivoted a pawl 153 pressed downwardly by a leaf spring 154. A rod 155 extending through an aperture in the table and lying in an open channel formed in the side face of the block 144 carries a pin 156 which lies just beneath the pawl 153. As the rod is raised it will swing the pawl on its pivot against the pressure of the spring 154 and thus keep the pawl out of operative engagement with the ratchet wheel. The block 144 carries a plate 157 suitably mounted so as to lie opposite the bite of the rolls 146 and this block 157 is provided with an aperture into which extends one of the flexible tubes 141. It will

be seen that when the lever 152 is rocked it will actuate the pawl and this movement of the pawl will cause the ratchet wheel to advance, provided the pawl is not held out of operative position by means of the rod 155, 70 and pin 156. This movement of the ratchet causes a rotation of the lower shaft 145 which is communicated to the upper shaft by the intermeshing gears 148. This causes a step-wise rotation of the feed rolls and advances the wire through the flexible tube to the feed block. The wire passes beyond the end of the feed block into the space in the block 89 in front of the forming devices where it is severed, formed into a 80 staple, and the staple inserted through a pair of links of the mesh and then closed so as to complete the link forming operation. 75

The various parts described in connection with the feeding of the wire are duplicated with each source of supply, the reel on which the wire is mounted in each case not being shown. In Fig. 2, however, it will be seen that the machine is designed to take care of wire of three different kinds. Consequently 85 there are three feed roll assemblies for each set of link forming tools, or in this case, six 90 in all. Each of these feeding devices is a duplicate of that shown in Fig. 25, and just 95 described.

The actuation of the feed ratchet pawls 154 is brought about as follows: The levers 152 are connected by links 158 to arms 159 which are fast on the shaft 107. One of these arms 159 terminates in an arm 160 which carries 100 a roller 161 bearing against a slightly eccentric cam 162 mounted on the shaft 55. This cam rotates with the main shaft and for each cycle of operation of the link forming tools the shaft 107 is rocked, thus causing 105 through the associated linkage, a movement of the pawls 153. However, as will presently be explained, only one of these pawls is permitted to cause feeding by reason of the action of the rod 155 and the pin 156. 110 In other words, at each operation of the link forming tools all of the feed ratchet pawls are actuated but only one of them produces 115 a feeding of the wire. The determination of which of these pawls shall operate and thus feed wire is carried on by the master control devices, and it will be seen that whichever pawl is permitted to be effective 120 will determine the kind of wire which is fed to the forming tools, and will therefore determine the color of the link which is inserted in the mesh at any particular point. 125

The principal parts of the master control device, which will now be described, are a color plate and a selector disc, and the color 125 plate forms the rotary support on which the control devices are adjustably positioned. In Figs. 1, 2, 3 and 11 there is illustrated a master control assembly for making mesh of a simple pattern containing stripes or 130

bands of different colors. The pattern device is of the type previously referred to as having a configuration which permits it to perform the same functions as the rotary support which carries the radial devices. Also, this particular assembly causes the pattern control mechanism to come into action only when the sleeve of mesh has made a complete rotation. Since two sets of link forming tools are used in this machine this rotation corresponds to the addition of a double row of links to the mesh. With this assembly, therefore, the pattern control device becomes operative at the end of each double row. This assembly which by reason of its simplicity in construction is here described, consists of elements as follows:

Mounted in a bracket 163 secured to the left-hand end of the machine, as illustrated in Figs. 1, 2 and 3 is a rock shaft 164 which carries at its inner end a bell crank 165, one arm of which is provided with a roller 166 which bears against the face of the cam 63 in such a position as to be engaged by a projecting and adjustably mounted plate 167 secured to the lower face of this cam. The other arm of the bell crank is connected to a spring 168 secured to the lower surface of the table and exerting tension so as to press the roller against the face of the cam. On the outer end of the rock shaft 164 is fixed an arm 169 on which is pivoted a spring-pressed pawl 170. This pawl bears against a ratchet wheel or selector disc 171, rotatably mounted on the rock shaft 164. Secured on the outer face of this selector disc is a dog 172 held adjustably in position by means of adjusting screws 173 which are mounted in suitable lugs on the face of the ratchet wheel. This dog projects beyond the periphery of the disc and once per revolution of the disc comes into engagement with a lug 174 formed on a lever 175, pivotally mounted on the clutch-actuating lever 176. This clutch-actuating lever is of L-shape, the long arm being horizontal and the short arm vertical. The long arm is mounted on bolts 177 secured in a pair of lugs extending downwardly from the bracket 163, these bolts extending through slots in the clutch-actuating lever so that the latter may be given a horizontal movement. Normally it is held in its extreme position to the right, as illustrated in Fig. 11, by means of a spring 178, one end of which is connected to a pin mounted on the lever, the other end to a pin mounted on one of the lugs forming part of the bracket. The lever 175 carrying the lug 174 is normally held in operative position, that is, in the position in which the lug will lie in the path of the dog 172 by means of a spring 179 pressed up against the free end of the lever.

Referring now to Figs. 3 and 12, it will be seen that mounted near the end of the

shaft 55, close to the hand wheel 58, is a collar 180. This collar is provided with a channel 181 in which lies a spring-pressed key 182. Mounted loosely on the shaft 55 next to the collar 180, is a double cam member 183, in which is formed a circumferential groove 184, adjacent the collar 180. This cam member is also provided with a channel 185 corresponding in shape to the channel 181. Lying on the opposite side of the double cam member 183 is another fast collar 186, also provided with a channel 187. The key 182 is shown in Fig. 11 as being dove-tailed, and the various channels in the collar and through the double cam member are of a similar shape. Riding in the channel 184 is an extension 188 formed on the end of the short leg of the bell crank 176 and this extension (shown in Fig. 12 in cross-section) has a wedge-like form. Also the key which extends into the channel has a beveled surface, against which this wedge bears. When the wedge-like extension lies in the channel, the rotation of the shaft 55, carrying with it the collar 180, will cause the key to ride up the wedge and so become disengaged from the channel in the double cam member. Accordingly, when the wedge is in position in this channel the key can have no effect in clutching the cam member to the shaft and the cam member therefore remains stationary. However, should the wedge be removed from the channel, then the spring will force the key along the dove-tailed slot so as to clutch the cam member to the shaft and the cam member will, therefore, become effective to produce a motion of its follower. This action takes place from time to time as follows: When the selector disc 171 has been advanced tooth by tooth, until the arm 172 bears against the lug 174, the next forward movement of the disc will cause the clutch-actuating lever 176 to be moved on its bolts, the extent of the movement being sufficient to disengage its extension from the channel 184. Thereupon, the spring-pressed key clutches the double cam member to the shaft to rotate with it. The double cam member 183 is provided with one surface 189 against which the spring-held end of the lever 175 normally bears. This surface is also provided with a riser 190. With this arrangement when the selector disc operates to throw in the clutch, the double cam member will be carried around with the shaft for one revolution, but at the instant when the selector disc is to be advanced the next step, then the riser 190 will strike the end of the lever 175 and move it downwardly so that the arm 172 will clear the lug 174. As soon as this clearance is effected, the spring 178 will restore the clutch-actuating lever to its normal position, and the clutch will be disengaged.

The larger surface of the double cam member has a depression 191, formed in its

periphery. Mounted at the rear of the bracket 163 is a stud 192, on which is pivotally mounted a rocking lever 193. A spring-pressed pawl 194 is pivotally mounted near the upper end of the lever, and the lever had integrally formed therewith an arm 195, terminating in a lug 196 which normally bears against the periphery of the double cam member. Also mounted on the stud 192 is a ratchet wheel 197, to which is secured a color plate 198 by means of a pin 199, threaded in the face of the ratchet wheel and extending into an aperture through the color plate. This color plate is held against the ratchet wheel by means of a spring washer, 200, held against the color plate by means of a threaded bolt 201. With this arrangement of parts, it will be seen that whenever the double cam member is clutched to the shaft 10 its rotation will present the depression 191 to the lug 196. A spring 202, one end of which is secured to the bracket 163, the other to the arm 195, thereupon causes the arm 195 to move downwardly, thus rocking the member 193 on its pivot and causing the pawl 194 to ride over a tooth on the ratchet wheel 197. When the depression 191 passes out from under the end of the lug 196 the member 193 will be restored to the normal position and the pawl will cause an advance of one step of the ratchet wheel, thus causing an advance in the color plate.

The color plate shown in Fig. 13 is designed so as to produce a single pattern which is indefinitely repeated and if a different pattern is to be produced the plate will be removed from the machine and another plate substituted. This arrangement differs somewhat from a form of color plate 35 which will later be described and which permits the pattern to be quickly changed without permanently altering the shape of the plate. The color plates, as has previously been described, is the means by which one 40 or the other of the wire feeds is brought into action and by which it is possible to determine in advance the number of links of a particular color which will be formed. This action of changing the feed from one 45 supply to another is brought about by rendering operative the feed pawl for the desired supply of wire, while the other feed pawls are kept inoperative. Since the color plate determines which of the wire feeds is 50 effective it must be designed to correspond with the number of different kinds of wire of which the mesh is being made. In the machine under consideration three different kinds of wire are used, and it will be noticed on an examination of Fig. 13 that the 55 color plate has portions of its periphery formed as arcs of different radii. These portions 203 have three radii corresponding to the three different kinds of wire. It will be noticed further that these portions have

varying lengths which, as will readily be seen, determine the extent to which a certain color is employed.

The control which is exercised over the wire feed by the color plate is brought about by means of an arm 204 pivotally mounted on a stud 205, mounted in an aperture in the bracket 163. A cam follower 206 which bears against the side face of the double cam member is secured adjustably to this arm and the cam member is provided with one riser 206' which serves to rock the arm 204 once per revolution of the double cam member. Mounted on one end of the arm 204 is a lug 207 which is placed in such a position that when the arm 204 is rocked this lug will strike against the edge of the color plate. Connected to the other end of the arm 204 is a link 208 suitably connected to the rock shaft 112, so that as the arm 204 is rocked by the double cam member the rock shaft will also be rocked. Secured on this rock shaft is a plurality of segments 209, one of which is clearly illustrated in Fig. 24. One of these segments is provided for each of the pairs of wire feed rolls, and each segment has a notch 210 formed in its rim. Freely mounted on the shaft 107 is a pivoted arm 211 carrying a roller 212, this roll bearing on the surface of the segment and being held thereagainst by means of a leaf spring 213. The end of the lever 211 bears against the lower end of a rod 155 which carries the pin 156 which may be moved to engage one of the wire feed ratchet pawls. As has been explained, there is one segment for each pair of wire feed rolls and each segment has a notch 210 located in a different position along its surface. When any segment is moved to such a position that the roller 212 will enter the notch then the arm 211 will drop down a slight distance. The rod 155 will also move downwardly and the pin 156 will free the wire feed ratchet pawl. Accordingly, when this condition has been set up then that pawl will become operative and upon the rocking of the shaft 107 causing the movement of the pawl, the latter will cause its ratchet to advance by one tooth, and thereby cause a feed of that particular kind of wire. The determination of which of these segments is brought into appropriate position depends on the shape of the color plate, as will now be explained.

When the double cam member has been clutched to the shaft its rotation will cause a rocking of the arm 204 which also causes a rocking of the shaft 112. The segments are all fast on this shaft and upon this rocking action each segment will be moved so that the roller 212 resting against it will ride up on a high point. This action consequently renders all of the wire feed ratchet pawls inoperative, but when the arm 204 is permitted to rock back, the extent of this

movement will depend on the radius of the surface of the color plate against which the lug 207 bears. The height of these surfaces is calculated so that when the lug bears 5 against any one of them, one or the other of the segments will be brought to rest in a position in which the roller 212 will enter a notch. Accordingly one of the wire feed pawls will be brought into action while 10 the others are kept out of engagement with their ratchets. Then, when the eccentric cam 162 rotates so as to rock the shaft 107, this particular pawl will cause the desired kind of wire to be fed. It will be seen, then, 15 that at every revolution of the double cam member all of the wire feed pawls are brought to inoperative position, and thereafter one of them is restored to operative position. In the machine which is now being 20 described, the double cam member will be clutched to the shaft but once during the rotation of the selector disc 171. A complete rotation of the disc corresponds to the completion of two rows of links in the sleeve, 25 one row being completed by each forming assembly. Since the disc rotates at this rate and has but one member on it which brings the color plate into action, the result is that the color is changed only when each assembly 30 has completed a full row or when two complete rows of the mesh sleeve are finished. The length of the surfaces 203 on the color plate determines how many times the selector shall operate before the color is 35 changed. If the length of a given surface is equivalent to ten teeth on the ratchet wheel by which the color plate is advanced, then the selector disc will make ten complete revolutions, each time bringing into action 40 the arm 207 which will bear against the appropriate surface on the color plate, but upon each of such movements the arm will bear against the same surface and consequently the color will not be changed. As 45 suming that the length of a surface corresponds to ten teeth of the ratchet wheel, then ten double rows of the mesh sleeve will be of the same color. The color plate may, therefore, be considered to control the pattern vertically of the sleeve of mesh, while 50 the selector disc determines the pattern across or around the mesh, as the case may be.

The plate 167 by which the selector disc 55 pawl is actuated is adjustable and as shown will cause the pawl to feed the disc one tooth at a time. By proper adjustment of this plate, however, the pawl may be given a greater throw; for instance, so as to feed 60 the disc two teeth at a time. Under these conditions the disc will rotate twice per complete rotation of the mesh sleeve, and this adjustment may be utilized to alter the pattern. With a throw of one tooth at a time 65 the selector disc acts to bring the color plate

into action once per double row of links formed, but with a feeding movement of two teeth at a time the selector disc will operate twice as often, and while the length of the control surfaces on the color plate 70 may now represent ten double rows, with the new arrangement each surface would be but one half as effective, and therefore would correspond to the production of five double rows. This adjustment of the throw 75 of the selector disc pawl permits of cutting down the widths of the bands, while making use of the same type of color plate.

Illustrated in Figs. 20 and 21 is a form of selector disc which brings the pattern device 80 into action at more frequent intervals and permits of variation in the length of these intervals. This selector disc 214 is secured to the face of the ratchet 171 by means of a pin which passes through an aperture 215 85 in the face of the disc. The disc 214 has a series of teeth 216, formed in its periphery and insertable between these teeth are blocks 217 illustrated in Figs. 22 and 23. These blocks project beyond the teeth and are 90 mounted so as to engage the lug 174 and actuate the clutch lever in the same manner as the arm 172. However, these blocks may be disposed in different positions about the rim of the disc 214 and as the latter is rotated the blocks are brought successively 95 into action against the lug. Thereafter, the color plate is moved in the manner previously described, and it may be advanced as frequently as may be required by the pattern simply by the proper arrangement of the blocks on the disc.

As has previously been explained, a selector disc may be provided which is so arranged that the formation of individual 105 links in a row is controlled, and such a selector disc is provided with an attachment such as is illustrated in Figs. 20 and 21. In connection with this selector disc there is used a color plate, such as is shown in 110 Figs. 14 and 15. This color plate is formed with peripheral teeth in which may be inserted blocks such as are illustrated in Figs. 16, 17, 18 and 19. These blocks are of varying 115 heights, depending on the different kinds of wire to be used, and in this instance there are blocks of three different heights to correspond with the three different kinds of wire. These blocks are set in position in the periphery of the disc and as the latter is advanced step by step at each period of rest one of the blocks will be positioned so as to be engaged by the lug 207 upon the return movement of the lever 204. Thus the 120 height of the blocks determines the position of rest which will be assumed by the lever and thus the blocks determine the position of the segments 209 which in turn determine 125 which of the wire feeds shall be operated.

When a color plate is used provided with 130

a series of peripheral blocks it follows that whenever the color plate has completed a revolution the pattern controlled by its peripheral blocks will be repeated. It may be 5 desirable, however, to make use of a pattern control which permits of less frequent pattern repetitions so that the figures produced in the mesh may be of greater length. For this purpose there may be substituted for the 10 color plate the disc 218 (see Figs. 31 to 36) the surface of which has a channel 219 in which runs a chain 220 on which may be mounted lugs 221, serving the same purpose as the blocks mounted on the disc illustrated 15 in Fig. 14. These lugs are detachably mounted on the chain and are formed with operating surfaces of heights corresponding in number to the kinds of wire to be employed. The chain which is to produce a 20 given pattern may be endless and is made up in advance by placing lugs on it of the desired heights in the required positions. This chain may be made of indefinite length, and at each advance of the disc a new lug is presented 25 to the lug 207. By making use of such a chain and a selector disc attachment as illustrated in Fig. 21, it is possible to produce a pattern in which each individual link of the mesh is selected and since the 30 chain may be of indefinite length the pattern formed in the fabric may be very long and composed of figures which are not repeated. However, even with a pattern of such extreme length it is also possible to 35 produce repetitions simply by making the chain endless.

It is to be understood, of course, that the various parts which go to make up the complete machine are properly timed and coordinated so that the mesh production is carried on without interruption. As each link forming assembly adds a link the sleeve is advanced one step and during this time a selected piece of wire will have been presented 40 to each of the assemblies. The forming tools thereupon operate to sever a length of wire, form the staple and insert the staple through a pair of links of the mesh and then close it. In the interval between successive 45 operations of the forming devices, the pattern mechanism has established the proper conditions so that the next link will be made of wire fed from the desired supply and the various cycles of operations continue so that a piece of mesh of indefinite length 50 is produced having recurring patterns formed by means of links of different colors. The pattern which is to be produced will depend on the form of the color plate or the assembly 55 of the blocks on the chain, and also on the arrangement of the selector disc mechanism. These parts will be arranged in advance and may be rapidly placed in operative position in a machine.

In Fig. 37 there is shown a piece of mesh

in which there are formed bands, A, B, and C, of different colors. Each of these bands is ten rows in width, and the control surfaces on the color plate will, therefore, be equivalent to five teeth on the color plate 70 ratchet, assuming that the selector disc brings the color plate into action once per complete double row of the finished mesh. In Fig. 38 there is illustrated a somewhat more complicated pattern, outlined by the 75 heavy lines. Various other patterns, of course, may be formed, and by making use of a color plate properly formed complicated designs may be turned out. These designs may be based on the use of more than 80 three kinds of wire, but in that event the machine will be provided with additional wire supplies, and the various parts by which wire from these supplies is fed to the forming devices.

While the present machine is designed to produce a mesh material having selected patterns appearing therein and formed by the inclusion of different colored links in the fabric, and this result is produced by a pattern mechanism including a selector disc and color plate, it will be understood that various changes and modifications in the parts as now illustrated may be made within the scope of this invention. For purposes of 90 illustration, the new invention has been shown embodied in a machine which produces mesh in the form of a sleeve which is given a step by step rotation past link forming tools and which is moved upwardly as 95 the links are added. With this type of machine production of patterned mesh it is brought about by controlling the wire which is fed to the link forming tools, but it will be seen that the same principles may be utilized in connection with a machine in which the links are formed of staples which are fed to the forming dies. In that type of machine a magazine of staples of each kind of wire may be provided for each of the forming dies and then these magazines may be brought into feeding position according to the kind of link which the pattern would require. Various mechanical constructions other than those here illustrated may be employed for 100 putting the principles of the invention into practice, but in any type of machine employing the present invention it is possible to control the formation of links according to a predetermined order of succession and to 105 arrange the mechanism so that the shift from one kind of link to another is selective both as to time and as to the kind of link material.

I claim:

1. A machine for making link mesh, comprising the combination of a support for a piece of mesh, link forming tools, power driven mechanism for giving the tools and the piece of mesh a step by step relative 110

movement and for operating the tools in each period of rest of this movement, a plurality of supplies of wire link material, a plurality of devices, one for each supply for feeding this material to the link forming tools, pattern mechanism for determining the supply from which material is to be fed and for controlling the action of the feeding devices, means for actuating the pattern mechanism, and means for controlling the operation of said actuating means.

2. A machine for making link mesh, comprising the combination of a support for a piece of mesh, link forming tools, power driven mechanism for giving the tools and the piece of mesh a step by step relative movement and for separating the tools in each period of rest of this movement, a plurality of supplies of wire link material, a plurality of devices, one for each supply, for feeding this material to the link forming tools, pattern mechanism for determining the supply from which material will be fed to the tools and the number of links which will be made from a selected material, means for actuating the pattern mechanism, and means actuated in accordance with the progress of the link forming operation for controlling the action of the actuating means.

3. A machine for making link mesh comprising the combination of a support for a piece of link mesh, link forming tools, power driven mechanism for operating the tools and for moving the tools and the piece of mesh relatively, a plurality of supplies of wire, a plurality of devices, one for each supply, for feeding wire to the link forming tools, a pattern mechanism for determining from which of these supplies of wire is to be fed, and means for actuating the pattern mechanism, the said means being brought into action only after the formation of a predetermined number of links.

4. A machine for making link mesh comprising the combination of a support for a piece of link mesh, link forming tools, power driven mechanism for operating the tools and for moving the tools and the piece of mesh relatively, a plurality of supplies of wire, a plurality of devices, one for each supply of wire, for feeding wire to the link forming tools, automatic mechanism operated by the power driven mechanism for selecting said several supplies so that wire will be fed to the link forming tools in a predetermined order of succession and for determining the number of links made from each supply before shifting to another one, means for actuating the automatic mechanism, and control means for the actuating means.

5. A machine for making link mesh comprising the combination of a support for a piece of link mesh, link forming tools, power driven mechanism for operating the tools

and for moving the tools and the piece of mesh relatively, a plurality of supplies of wire, a plurality of devices, one for each supply of wire, for feeding wire to the link forming tools, an automatic contrivance operated by the power driven mechanism for effecting a shift in the said wire feeding devices so that wire will be fed to the link forming tools from said several supplies in a predetermined order of succession, and means for operating the contrivance, the said means being actuated in correspondence with the operation of the link forming tools but acting upon the contrivance only upon the completion of a predetermined number of links by the tools.

6. A machine for making link mesh which comprises a support for a piece of mesh, means for forming links intermeshing with those of the piece of mesh, a plurality of supplies of wire link material, means for selecting a supply of link material according to a predetermined pattern and causing this material to be fed from the selected supply to the link forming means, means for operating the selecting means, and means for controlling the operating means.

7. A machine for making link mesh which comprises a support for a piece of mesh, means for forming links intermeshing with those of the piece of mesh, a plurality of supplies of wire link material, means for feeding material from said supplies to the link forming means, means for controlling the action of the feeding means in accordance with a predetermined pattern, means for actuating the control means, and means for controlling the action of said actuating means.

8. A machine for making link mesh which comprises a support for a piece of mesh, means for forming links intermeshing with those of the piece of mesh, a plurality of supplies of wire, wire feeding means associated with each of said supplies, pattern controlled means operable to render one of the feeding means operative while the others are maintained inoperative, the said pattern controlled means having a plurality of effective portions, and means for rendering the several portions of the pattern controlled means successively effective at intervals throughout the progress of the mesh-making operation.

9. A machine for making link mesh, which comprises a support for a piece of mesh, means for forming links intermeshing with the links of the piece of mesh, a plurality of supplies of wire, means associated with each of these supplies for engaging the wire and feeding it therefrom to the link forming means, a pattern device for bringing one of the wire feeding means into operation while the others are maintained at rest, means for actuating said pat-

tern means, and means for modifying the action of said actuating means.

10. A machine for making link mesh fabric, which comprises a support for a piece of mesh, means for forming link intermeshing with the links of the piece of mesh, a plurality of supplies of wire, means associated with each supply for feeding wire therefrom to the link forming means, a color plate movable to different positions and in each position operable to select and render effective one of said wire feeding means while maintaining the others inoperative, and means for moving the color plate only 15 after the completion of a predetermined number of links.

11. A machine for making link mesh which comprises means for supporting a piece of mesh, means for forming links intermeshing with those of the piece of mesh, a plurality of supplies of wire, means associated with each of said supplies and operable one at a time for feeding wire therefrom to the link forming means, a movable device 25 for selecting and bringing the wire feeding means into action in a predetermined order of succession, and means operable only after the formation of a predetermined number of links for moving the said device.

30. 12. A machine for making link mesh which comprises means for supporting a piece of mesh, means for forming links intermeshing with those of the piece of mesh, a plurality of supplies of wire, means for 35 feeding wire from each supply to the link forming means, a plate movable to different positions and in each such position operable to select and render effective one of the wire feeding means, and means operable only 40 after the completion of a predetermined number of links for moving the plate.

13. A machine for making link mesh which comprises means for supporting a piece of mesh, means for forming links intermeshing with those of the piece of mesh, a plurality of supplies of wire, means for feeding wire from each of said supplies to the link forming means, a rotary plate, means for advancing the plate only after the 45 completion of a predetermined number of links, and means operable under the control of the plate for actuating one of the wire feeding means.

14. A machine for making link mesh, 55 which comprises means for supporting a piece of mesh, means for forming links intermeshing with those of the piece of mesh, a plurality of supplies of wire, means for feeding wire from each of said supplies to the link forming means, a plate having portions 60 thereof formed in accordance with a predetermined pattern and operable to select the supplies in a predetermined order of succession, means controlled by the said 65 portions of the plate for actuating the feed-

ing means associated with a selected supply, and means operable upon the completion of a predetermined group of links for advancing the plate to bring another portion into effective position.

15. A machine for making link mesh, which comprises a support for a piece of mesh, means for forming links intermeshing with those of the piece of mesh, a plurality of supplies of wire, feeding means associated with each of said supplies, a pattern mechanism for controlling the action of said feeding means, this mechanism acting upon the feeding means to change the action of the latter to cause the wire to be fed in a predetermined order of succession, and means for bringing the pattern mechanism into action upon the completion of a predetermined group of links.

16. A machine for making link mesh which comprises a support for a piece of mesh, means for forming links intermeshing with those of the piece of mesh, a plurality of supplies of wire, feeding means associated with each of the said supplies, and a pattern mechanism for changing the feed from one supply to another, this mechanism including a plate having portions thereof arranged in accordance with a predetermined pattern, and means for bringing these portions into effective controlling position upon the completion of a predetermined group of links.

17. A machine for making link mesh which comprises a support for a piece of mesh, means for forming links intermeshing with those of the piece of mesh, a plurality of supplies of wire, each supply having wire feeding means associated therewith, and means for controlling the action of said feeding means, comprising a member actuated upon the formation of a predetermined group of links, and another member made effective to change the feed upon the completion of a predetermined number of said groups.

18. A machine for making link mesh, which comprises a support for a piece of mesh, means for forming links intermeshing with those of the piece of mesh, a plurality of supplies of wire, each of said supplies having wire feeding means associated therewith, means for rendering said feeding means operative or inoperative and a pattern mechanism for controlling the action of said last named means, this pattern mechanism including a selector disc actuated in accordance with the operation of the link forming tools but operative only upon the completion of a predetermined number of links and a color plate for determining the order of succession in which the wire is fed and brought into action by the selector disc.

19. A machine for making link mesh,

which comprises a support for a piece of mesh, means for forming links intermeshing with those of the piece of mesh, a plurality of supplies of wire, each of said supplies having wire feeding means associated therewith, means for rendering said feeding means operative or inoperative, and a pattern mechanism for controlling the action of the wire feeding means, this pattern mechanism including a selector disc movable step-wise, one step as each link is formed and a color plate brought into action to change the feed upon completion of a predetermined number of said steps.

20. A machine for making link mesh which comprises a support for a piece of mesh, means for forming links intermeshing with those of the piece of mesh, a plurality of supplies of wire, means associated with each of said supplies for feeding wire therefrom to the link forming means and a pattern mechanism for rendering one of said wire feeding means operative while maintaining the others inoperative, this pattern mechanism including a color plate having a plurality of effective portions, a member controlled by the color plate in turn controlling the action of the feeding means, and a selector disc movable step-wise and operable to bring successive portions of the color plate into effective position upon the formation of predetermined numbers of links.

21. A machine for making link mesh which comprises a support for a piece of mesh, means for forming links intermeshing with the links of the piece of mesh, a plurality of supplies of wire, means associated with each of said supplies for feeding wire therefrom to the link forming means, a pattern mechanism for controlling the action of said wire feeding means, said pattern mechanism including a selector disc made operative upon the completion of a predetermined number of links, a color plate brought into action by the operation of said selector disc and effective to determine the order of succession in which the wire will be fed to the link forming means and means controlled by said color plate for rendering one of said wire feeding means operative while maintaining the others in inoperative position.

22. A machine for making link mesh which comprises a support for a piece of mesh, means for forming links intermeshing with the links of the piece of mesh, a plurality of supplies of wire, means associated with each of said supplies for feeding wire therefrom to the link forming means, a pattern mechanism for controlling the action of said wire feeding means, including a selector disc rendered operable upon the completion of a predetermined number of links, a color plate movable by said selector disc and effective to determine the order of succession in

which the wire will be fed to the link forming means and means controlled by the color plate and in turn controlling the action of said wire feeding means.

23. A machine for making link mesh, 70 which comprises a support for a piece of mesh, means for forming links intermeshing with the links of the piece of mesh, a plurality of supplies of wire, means associated with each of said supplies for feeding wire therefrom to the link forming means, a pattern mechanism for controlling the action of said wire feeding means and including a selector disc rendered effective upon the completion of a predetermined number of links, a color 80 plate having color control areas disposed thereon, and means brought into action by said selector disc and acting to render one of said wire feeding means operative while the others are maintained inoperative under 85 the control of one of the control areas on the plate.

24. A machine for making link mesh, comprising the combination of a support for a piece of link mesh, link forming tools, power 90 driven mechanism for operating the tools and for moving the tools and the piece of mesh relatively, a plurality of supplies of wire, a plurality of wire feeding devices, one for each supply of wire, and an automatic control mechanism for controlling the operation of said wire feeding means comprising a movable member connected to the power driven mechanism to be operated thereby in correspondence with the operation of the link forming tools, an element mounted on and movable with said member, a second movable member actuated by the power shaft under the control of said element and an element coacting with said second movable member and determining by its position which of the said wire feeding devices shall operate and which shall remain inactive. 100

25. A machine for making link mesh which comprises the combination of a support for a piece of mesh, means for forming links intermeshing with the links of the piece of mesh, a plurality of supplies of wire, means associated with each of said supplies for feeding wire therefrom to the link forming means, and a pattern mechanism for controlling the action of said wire feeding means including a selector disc having portions thereof brought into operative position upon the completion of a predetermined number of links, a color plate having color control areas disposed thereon in accordance with a predetermined pattern, and a member brought into action by the portions of the selector disc referred to and operable under the control of the areas on said plate for rendering one of said wire feeding means operative while the others are maintained inoperative. 110

26. A machine for making link mesh 130

- which comprises a support for a piece of mesh, means for forming links intermeshing with those of the piece of mesh, a plurality of supplies of wire, means associated with each of said supplies for feeding wire therefrom to the link forming means and a pattern mechanism for rendering one of said wire feeding means operative while maintaining the others inoperative, this pattern mechanism including a color plate for selecting and rendering operative the selected wire feed, this color plate having control areas arranged in series thereon, a selector disc movable step-wise during the progress of the link-forming operation, and means operated by said disc upon the completion of a predetermined number of steps for bringing successive areas of the color plate into effective position.
27. A machine for making link mesh which comprises means for supporting a piece of mesh, means for forming links intermeshing with those of the piece of mesh, a plurality of supplies of wire, means for feeding wire from each of said supplies to the link forming means and a pattern mechanism for selecting and rendering operative one of said wire feeding means, this pattern mechanism including a selector disc rendered effective upon the completion of a group of links and a color plate brought into action by the selector disc upon the completion of a predetermined number of such groups and thereupon effective to change the feed from one source of supply to another.
28. A machine for making link mesh which comprises means for supporting a piece of mesh, means for forming links intermeshing with those of the piece of mesh, a plurality of supplies of wire, means for feeding wire from each of said supplies to the link forming means and a pattern mechanism for selecting and rendering operative one of said wire feeding means, this pattern mechanism including control means rendered effective only after the completion of a predetermined number of links and means cooperating with the control means to determine the source of supply from which wire shall be fed and operating to change from one supply to another when the control means has become effective a predetermined number of times.
29. A machine for making link mesh which comprises means for supporting a piece of mesh, means for forming links intermeshing with those of the piece of mesh, a plurality of supplies of wire, means for feeding wire from each of said supplies to the link forming means and a pattern mechanism for selecting and rendering operative one of said wire feeding means, this pattern mechanism including a selector disc movable upon the formation of each link and having a member thereon rendered effective after a

predetermined movement corresponding to the completion of a group of links and means for controlling the action of the wire feeding means and including a series of control areas brought successively into action by 70 said member.

30. A machine for making link mesh which comprises means for supporting a piece of mesh, means for forming links intermeshing with those of the piece of mesh, a plurality of supplies of wire, means for feeding wire from each of said supplies to the link forming means and a pattern mechanism for selecting and rendering operative one of said wire feeding means, this pattern mechanism including a selector disc movable as each link is formed, and having a member thereon brought into action upon the completion of a predetermined movement of said disc, pattern means for determining the order of succession in which the wire is fed to the link-forming means, the said pattern means being provided with a plurality of control areas and being given successive movements by the members to bring the areas successively into action, and means controlled by said pattern means for rendering a single wire feeding means effective.

31. A machine for making link mesh which comprises means for supporting a piece of mesh, means for forming links intermeshing with those of the piece of mesh, a plurality of supplies of wire, means for feeding wire from each of said supplies to the link forming means and a pattern mechanism for controlling the action of said wire feeding means and including a selector disc movable stepwise as each link is formed, means for rendering one of said wire feeding means operative while maintaining the others inoperative and means controlling the order of succession in which the wire is fed to the link-forming means, the said means including a plurality of control areas brought successively into action upon a predetermined movement of the selector disc.

32. A machine for making link mesh, which comprises a support for a piece of mesh, means for forming links intermeshing with the links of the piece of mesh, a plurality of supplies of wire, a ratchet associated with each of said supplies of wire for feeding wire therefrom, a continuously operated pawl associated with each ratchet, means acting upon each pawl for moving the latter into and out of operative position, and means for controlling the action of said last named means according to a predetermined pattern.

33. A machine for making link mesh, which comprises a support for a piece of mesh, means for forming links intermeshing with the links of the piece of mesh, a plurality of supplies of wire, a ratchet associated with each of said supplies of wire for 130

feeding wire therefrom, a pawl associated with each ratchet and operable upon the formation of each link, means for rendering said pawls effective or ineffective to actuate said ratchets and a pattern mechanism for controlling the action of said last named means according to a predetermined design.

34. A machine for making link mesh which comprises a support for a piece of mesh, means for forming links intermeshing with the links of the piece of mesh, a plurality of supplies of wire, a ratchet associated with each of said supplies of wire for feeding wire therefrom, a pawl associated with each ratchet and operable upon the formation of each link, means for rendering said pawls effective or ineffective to actuate said ratchets, a color plate for controlling the action of said last named means and a selector disc for rendering said color plate operative to change the feed upon the formation of a predetermined number of links.

35. A machine for making link mesh, which comprises a support for a piece of mesh, means for forming links intermeshing with the links of the piece of mesh, a plurality of supplies of wire, rotary means associated with each supply for engaging and feeding wire therefrom, continuously operated driving means for said rotary means, and means for rendering the driving means successively effective according to a predetermined pattern.

36. A machine for making link mesh, which comprises a support for a piece of mesh, means for forming links intermeshing with the links of the piece of mesh, a plurality of supplies of wire, means continuously engaging the wire from each supply and operative to draw wire therefrom and feed it to the link forming means, driving means for the wire feeding means, and means for controlling the action of said driving means to render them successively operable according to a predetermined pattern.

37. In a machine for making link mesh containing links of different kinds of wire, the combination of a plurality of supplies of wire link material, means for incorporating links from any supply in a fabric containing rows of links extending transversely of the fabric, and means for selecting the material to be used in accordance with a predetermined pattern, the said means being provided with a plurality of control areas brought successively into action only after the completion of a predetermined number of links in a row in said fabric.

38. In a machine for making link mesh containing links of different kinds of wire, the combination of a plurality of supplies of wire link material, means for incorporating links from any supply in a fabric containing rows of links extending transversely of the fabric, and means for selecting the

wire to be incorporated in accordance with a predetermined pattern, the said means including a plurality of control areas successively effective upon the completion of a predetermined number of links, the number of links in a row in the fabric being a multiple of said predetermined number.

39. In a machine for making link mesh containing links of different kinds of wire, the combination of a plurality of supplies of wire, means for incorporating links in the fabric, means for feeding wire from a supply to the means last mentioned, and means for controlling the action of the wire feeding means whereby the wire is fed in a predetermined order of succession, the said control means being operable only after the completion of a predetermined number of links in said fabric.

40. In a machine for making link mesh containing links of different kinds of wire, the combination of a plurality of supplies of wire link material, feeding means associated with each of said supplies, means for actuating each feeding means and a pattern control device for rendering said feeding means effective one at a time, said pattern device including a color plate, an arm bearing thereagainst and operatively connected to said actuating means, and a selector disc operable to advance the color plate periodically.

41. In a machine for making link mesh containing links of different kinds of wire, the combination of a plurality of supplies of wire, feeding means associated with each of said supplies, means for actuating each of said wire feeding means and a pattern control device for rendering one of said wire feeding means effective while maintaining the others ineffective, said pattern device including a color plate containing color control areas successively arranged thereon, operative connections between said color plate and said wire feeding means, and a selector disc operable upon the completion of a predetermined number of links for bringing the control areas on the color plate successively into effective position.

42. A machine for making link mesh, which comprises a support for a piece of mesh, means for forming links intermeshing with the links of the piece of mesh, a plurality of supplies of wire, means for feeding wire from one of said supplies to the link forming tools according to a predetermined pattern, and a guide for leading the wire being fed to said tools, this guide also being movable to operative position in accordance with the pattern.

43. A machine for making link mesh, which comprises a support for a piece of mesh, means for forming links intermeshing with the links of the piece of mesh, a plurality of supplies of wire, feeding means associated with each of said supplies, means

for guiding the wire being fed to the link forming tools and means for controlling the wire feeding means and the guiding means according to a predetermined pattern.

- 5 44. In a machine for making link mesh containing links of different kinds of wire, the combination of link forming means, means for feeding wire thereto from a plurality of supplies, means for actuating a selected feeding means, means for guiding the wire fed to the forming means, and a pattern control device for controlling the action of said feeding means and said wire guide.
- 10 45. A machine for making link mesh including a support for a piece of mesh, means for forming links intermeshing with those of the piece of mesh, a plurality of supplies of wire, means for feeding wire from a selected supply, means for guiding the wire so fed to

- 20 the link forming means, including a reciprocable block having a channel for the wire from each supply, and means for controlling the action of said feeding means and for positioning said block with the appropriate
- 25 channel in effective position.

46. A machine for making link mesh comprising the combination of a support for a piece of mesh, link forming tools, power driven mechanism for giving the piece of mesh and the tools a relative step by step movement and for operating the tools in the periods of rest of this movement, a plurality

of supplies of wire, means for feeding this wire to the link forming tools, movable means for guiding the wire being fed to the tools, and a selecting means operated by the power driven mechanism for selecting the supply from which the wire is to be fed and for moving the guiding means to a position in which the said means guides the wire being fed to the link-forming tools.

47. A machine for making link mesh, comprising the combination of a support for a piece of mesh, link forming tools, power driven mechanism for giving the piece of mesh and the tools a relative step by step movement and for operating the tools in the periods of rest of this movement, a plurality of supplies of wire, a plurality of devices, one for each supply, for feeding the wire from these supplies to the link forming tools, a movable block having a guide passage for the wire from each supply, this block serving, in its different positions of adjustment, to guide one of the wires to the link forming tools, and a pattern device operated by the power driven mechanism for causing the wire to be fed to the tools in a predetermined order of succession and for causing the block to be moved to different positions of adjustment corresponding to the kind of wire which is to be fed.

In testimony whereof I affix my signature.
OSCAR SODERSTROM.
